UNITED STATES PATENT OFFICE.

THEODOR SAMUEL ESTEL, OF PLATTE CENTER, NEBRASKA.

COOP.

1,172,777.

Specification of Letters Patent.

Patented Feb. 22, 1916.

Application filed May 22, 1914. Serial No. 840,304.

To all whom it may concern:

Be it known that I, THEODOR SAMUEL ESTEL, citizen of the United States, residing at Platte Center, in the county of Platte and State of Nebraska, have invented certain new and useful Improvements in Coops, of which the following is a specification.

My invention relates to improvements in hen coops or cages, and particularly to a coop or cage, such in its nature as to be suspended, by any suitable means, above the ground.

It is a well known fact that laying hens will in the spring of the year, invariably brood, which brooding can only be stopped by cooping the hen and depriving her of food. The above method, even though almost universally adopted, often proves inefficient to prevent continued brooding on the part of the hen.

With the above in view, it is the primary object of the present invention to so construct and support a cage or coop as to provide for a circulation of cool air under the hen while brooding, the result of the cooling action, as has been proven upon test, causing the hen to cease brooding and to again start laying as before.

The above and additional objects are accomplished by such means as are illustrated in their preferred embodiment in the accompanying drawings, described in the following specification and then more particularly pointed out in the claims which are appended hereto and form a part of this application.

In describing my invention in detail reference will be had to the accompanying drawings wherein like characters denote like or corresponding parts throughout the several views, and in which:—

Figure 1 is a perspective view of a cage or coop constructed in accordance with the present invention; Fig. 2 is a fragmentary sectional view illustrating the manner in which the floor of the coop is held in place; and Fig. 3 is a similar view illustrating the manner in which the roof or top of the coop is so held.

Referring now to the drawings by numerals, 1 designates the floor of the cage, said floor comprising a plurality of uniformly spaced parallel slats or strips, so arranged relatively to a suitable frame 2 as to be inclosed thereby. Adjacent the

respective four corners of the floor (the same being preferably square) is coiled a wire strand 3, two strands being used, each of which is bent after the fashion of an inverted U to form corner braces or standards 4, the connecting portion 5 of each strand serving as a means of support for the roof 6, the opposite longitudinal edges of which are coiled as at 7 about the respective connecting portions of the said strand, the said connecting portions extending parallel. To provide for drainage, the roof 6 is preferably corrugated as shown.

The four sides of the coop are covered with a wire mesh designated 8, one of the said sides being so arranged as to swing outwardly or away from one corner of the coop to in this manner serve as a door whereby egress and ingress to the coop may be had. Any suitable fastening means may be provided to hold the door side of the coop closed.

The terminals of the respective wire strands are coiled about the longitudinal edges of the frame 2 as indicated at 9, preferably as shown to advantage in Fig. 2.

As a means whereby the cage or coop may be suspended above the ground, I provide two wire strands bent as shown in Fig. 1 to overlap a hook designated 11, the latter being supported by the limb of a tree or, if desired, from any suitable structure, immaterial in its nature.

By the above formation, it is apparent that the hen when attempting to brood, and upon entering the coop or cage, will sit upon the floor 1, and, as the said floor is suspended above the ground and further, as the floor construction provides for the circulation of cool air beneath the hen, such circulation, by reason of its cooling effect, will, in a short period of time so affect the hen, as to nullify the brooding desire, and in the end cause the hen to again commence laying as before.

From the foregoing, taken in connection with the accompanying drawings, it is to be noted that the construction of the coop is simple in the extreme; that by having the open nest sides, the entire interior of the coop is subjected to cooling influence of the air without; and that the troublesome method of discouraging brooding adopted heretofore as above set forth is completely eliminated, an efficient, practical and inexpensive coop or cage being substituted therefor.

In reduction to practice, I have found that the form of my invention, illustrated in the drawings and referred to in the above description, as the preferred embodiment, is 5 the most efficient and practical; yet realizing that the conditions concurrent with the adoption of my device will necessarily vary, I desire to emphasize the fact that various minor changes in details of construction, 10 proportion and arrangement of parts may be resorted to, when required, without sacrificing any of the advantages of my invention, as defined in the appended claims.

Having thus fully described my invention, 15 what I claim as new and desire to secure by Letters Patent, is:—

1. A collapsible coop comprising a floor portion made up of a plurality of spaced slats to provide for the circulation of air
- 20 therethrough, a frame for the sides of the coop consisting of wire strands bent substantially U-shaped, the respective wire strand terminals being coiled about the floor portion adjacent the respective corners of
- 25 the coop, sides made up of a single strip of

wire netting bent to embrace the frame and to leave an entrance and exit opening therein, a roof comprising a single strip of im- 30 perforate sheet metal having its opposite edges coiled to embrace the respective connecting portions of the U-shaped strands, and means to suspend the coop in a position to provide for bodily swinging movement thereof for the purpose specified.

2. A coop comprising a floor of a construction permitting the circulation of air therethrough, a wire frame, means bent to encircle the frame in a manner leaving an entrance opening and exit opening therein, a roof consisting of a single strip of im- 40 perforate material having its opposite edges coiled to embrace portions of the wire frame, and means to suspend the coop for bodily swinging movement.

In testimony whereof I affix my signature 45 in presence of two witnesses.

THEODOR SAMUEL ESTEL.
